UNITED STATES PATENT OFFICE

ALFRED SCHNABEL, OF NEW YORK, N. Y.

TOBACCO CONTAINER WITH PIPE-FILLING MEANS

Application filed June 14, 1928. Serial No. 285,309.

This invention relates to containers for pipe tobacco and has for its object to equip the container with means for discharging the tobacco therefrom directly into a pipe, thereby greatly facilitating the filling of a pipe and eliminating waste.

Another object is to provide means whereby a quantity of tobacco necessary to fill the pipe will be discharged by a single operation.

A still further object is to provide means for preventing spilling of tobacco through the discharge opening while the container is not in use.

15 With these and other objects in view my invention consists substantially in the novel construction, combination and arrangement of parts as will be hereinafter more fully described.

20 In the accompanying drawing in which similar reference characters denote corresponding parts, Fig. 1 is a vertical section of a tobacco container and of the tobacco discharging device; Fig. 2 is a cross section 25 on line 2—2 of Fig. 1; Fig. 3 is an enlarged section on line 3—3 of Fig. 1; Fig. 4 is a similar section to that of Fig. 1 on a still larger scale, with the discharging device in projected position; Fig. 5 is a cross section 30 on line 5—5 of Fig. 1; Fig. 6 is a perspective view of a modified structure; Fig. 7 is a longitudinal section thereof and Fig. 8 is a cross section on line 8—8 of Fig. 7.

Referring more in detail to the drawings 35 and first to the construction shown in Figs. 1 to 5, 10 denotes a container or can made of sheet metal or other suitable material having a hinged lid 10^a and a circular discharge opening 10^b in one of its walls. By 40 a longitudinal partition 11 the casing is divided into a main compartment 10^c to contain the tobacco and a compartment 10^d to contain some parts of the tobacco discharging means. Fixed to and extending transversely from the inner face of said longitudinal partition 11 is a substantially trough shaped platform 12 advantageously arranged in a slanting manner toward but terminating some distance off said discharge opening, 45 said platform serving as a bottom for the

main compartment on which the tobacco will tend to slide down and fill the space behind the discharge opening 10^b to be subsequently discharged into the bowl of a smoking pipe, as will be presently described. Below the 55 platform 12 I provide a tubular shell or guide 13 suitably fixed to the bottom of the casing 10 as by soldering or otherwise and which extends transversely of the casing in alignment with said discharge opening. In 60 this shell is movably borne a cylindrical plunger 14 of a diameter equal to that of the discharge opening 10^b. This plunger on its upper face is provided with a hood shaped extension 14^a which when the plunger 65 is projected forwardly is adapted to serve as a roof over the space behind the discharge opening 10^b to prevent tobacco falling into said space during the filling operation. In this space I provide a trough shaped shell 15 having a semi-cylindrically curved bottom 15^a in extension of the shell 13 and which when the plunger 14 is advanced will be closed by the hood or roof 14^a. The plunger 14 is provided centrally 70 with a stem or rod 16 extending through a stationary support or bearing 17 and formed at its free end with an enlargement or breast plate 17^a. A spring 18 mounted around the rod between the said bearing and 75 enlargement tends to retract the plunger into the position shown in Fig. 1, so that a quantity of tobacco from the main compartment may drop into the shell 15. A push member 19 is slidably mounted on the 80 bottom of the casing at the rear of the enlarged end 17^a of the rod 17 and is suitably guided in a slot 10^c in said bottom. The lower end of said push member is formed with a grasp 19^a. A spring 20 arranged between the stationary support 16 and said push member 19 tends to hold the latter in 85 retracted position. The discharge opening 10^b is adapted to be normally closed by a slide or the like 21 which is mounted on the inner face of the wall in which the discharge opening is formed. The slide is suitably guided as at 21^a in a longitudinal direction of the casing 10 and is adapted to be 90 operated automatically simultaneously with 95 100

the operation of the plunger 14 by the following mechanism. Extending transversely through the compartment 10^b is a rack 22 which through a gear 23 meshes with a rack 24 projecting from the inner face of the slide 21. The rear end of the rack 22 carries two independently rotatable double armed levers 25 fulcrumed at 25' thereto. The ends of the arms of one pair 25^a project into the path of the push member 19 while in the path of the arms 25^b of the other pair is provided a cam member 26. Normally, i. e. when the push member 19 is in retracted position one of the arms 25^a is located just in front of the push member, so that when the latter is moved forwardly to operate the plunger 14 as will be presently described, it will also move the rack 22 which through the gear 23 and the rack 24 will move the slide 21 into open position. When the push member is in its extreme forward position the other of the two arms 25^a will have dropped to lie close to and at the rear of said member so that on the return stroke of the latter said arm will engage and thereby move the rack 22 along and consequently through gear 23 and rack 24 also move the slide 21 into closing position. The cam faces 26^a at the ends of the member 26 will cooperate with the ends of the arms 25^b to turn the levers 25 so as to lift one or the other of their lower arms 25^a out of the path of the push member, as shown in Figs. 1 to 4.

The operation of the device is as follows: 35 When the container or rather its compartment 10^a is filled with smoking tobacco, and while the same is not in use, the discharge opening 10^b is closed by the slide 21 and the plunger 14 being in retracted position, the tobacco is allowed to freely drop into the shell or chamber 15 which is so admeasured as to hold a quantity necessary to fill a pipe of ordinary size in one operation. To do that the container is grasped in one hand 40 and by the palm of the hand the tobacco pipe is pressed with the mouth end of its bowl against the discharge opening, while by a finger of the other hand the push member 19 is advanced. This causes first the slide or closure 19 to be moved into open position through the medium of one of the arms 25^a of the levers 25, rack 22, gear 23 and rack 24 in the aforescribed manner. During this time the plunger 14 remains at 45 rest. When the push member 19 has reached the enlargement or breast plate 17 it engages the latter and on continuing its forward movement it will move the plunger 15 forwardly against the tension of its spring 20, thereby expelling the tobacco from the space or chamber 15 into the bowl of the pipe. At the same time the hood portion 14^a of said plunger will close the chamber 15 against the compartment 10^a prevent-

ing the tobacco from dropping into it during the filling operation.

After the pipe is filled, the grasp 19' of the push member 19 is released which by the contraction of its spring 20 will be forced back into the initial position. During this movement the push member 19 by acting against the forward arm 25^a of the pair of levers 25 will first operate the slide 21 closing the discharge opening. As the push member recedes from the breast plate 17' the plunger 14 is forced by its spring 18 to return into initial position, and the hood 14' thereof uncover the chamber 15 permitting a fresh supply of tobacco to drop into it for the next filling.

This construction is adapted to be used with specially sized and shaped receptacles. It may be desirable to apply a pipe filling device to the ordinary tin cans of usual shape and size, which in size are greatly limited. In such case a simplified device must be used, of which an embodiment is shown in Figs. 6-8.

Here 27 is a tin can of conventional shape and size in which the pipe tobacco is packed without the usual paper wrapper. In one of the walls, as in the bottom of the can, the circular discharge opening 27' is provided which is adapted to be closed by a slide 28 or the like to be manipulated by hand by means of a grasp 28'. In alignment with said discharge opening and spaced therefrom I provide a cylindrical or tubular chamber or shell 29 extending to the opposite wall of the casing. Inside said chamber is movably borne a plunger 30 of wood or other suitable material which at its rear is formed with a grasp 30' projecting through a longitudinal slot 27^a of the can. The space 31 between the discharge and the front end of the plunger or chamber is admeasured to hold the quantity sufficient to fill a pipe in one stroke.

In this modification the platform is omitted, but the feeding of the tobacco into the space 31 can be easily effected by holding the can in the position shown in Fig. 7 and slightly shaking it before use.

It is of course conceivable that the construction of the device may be varied in many ways without departing from the principle of my invention.

I, therefore, do not wish to restrict myself to the details described and shown.

What I claim is:

1. A tobacco container having a discharge opening, a movable closure means for said opening, a tubular shell in said container in alignment with said opening, a platform above said shell for guiding tobacco to a compartment between said shell and said opening, a separate compartment for said container containing operating means for said closure means, a plunger in said shell,

means to operate said plunger to eject said tobacco through said opening and means connecting said plunger operating means and closure operating means whereby said closure will open before said plunger is actuated and close when said plunger is retracted.

5 2. A tobacco container having a discharge opening, a tubular shell in alignment with and of the same dimension as said opening, 10 a compartment between said shell and discharge opening to receive a quantity of tobacco from said container sufficient to fill a pipe, a plunger in said shell which when moved forwardly will expell the said quantity of tobacco through said discharge into 15 the bowl of a pipe held against said discharge, closure means for said opening, means for actuating said plunger and means operated by said plunger actuating means 20 for opening said closure means before said plunger moves forwardly and for closing said closure means immediately when said plunger begins to retract upon release.

3. In a tobacco container having a discharge opening, a movable closure means for 25 said opening and a spring returned plunger for ejecting tobacco in said container through said opening, means for operating said plunger and closure means, said operating means including a push member slidably 30 mounted in said container, means for returning said member to initial position, means for transmitting the sliding motion of said member to open said closure means, 35 said transmitting means including a pair of independently movable stops mounted to said transmitting means and projecting into the path of said push member and cam operated means for removing said stops from 40 the path of said push member during portions of its movement whereby said closure means will be opened before said plunger moves forwardly to eject tobacco and will close when said plunger moves rearwardly.

45 In testimony whereof I affix my signature.
ALFRED SCHNABEL.
